TONGUE FOR A SHOE

Horst B. Dassler, Eckartswiller, France, assignor to Adidas, Landersheim, France

Filed Oct. 18, 1971, Ser. No. 190,436

Claims priority, application France Apr. 23, 1971

Term of patent 14 years

Int. Cl. D2—04

U.S. Cl. D2—314

FIG. 1

FIG. 5

FIG. 2

FIG. 3

FIG. 4

FIG. 1 is a plan view of a tongue for a shoe showing my new design;

FIG. 2 is a plan view of a second embodiment of the design of FIG. 1 with the portion thereof broken away being like that shown in FIG. 1;

FIG. 3 is a plan view of a third embodiment of the design;

FIG. 4 is a plan view of a fourth embodiment of the design; and

FIG. 5 is an elevational side view of the edge of the tongue for a shoe embodying my new design.

The edge and bottom of the tongue shown are plain having no design features.

I claim:

The ornamental design for a tongue for a shoe, substantially as shown and described.
